UNITED STATES PATENT OFFICE.

JOHANN ORTNER, OF CLEVELAND, OHIO, ASSIGNOR OF ONE-THIRD TO
HERMANN H. RIPPE, OF CLEVELAND, OHIO.

WHEEL-FENDER.

SPECIFICATION forming part of Letters Patent No. 766,195, dated August 2, 1904.

Application filed November 7, 1903. Serial No. 180,197. (No model.)

To all whom it may concern:

Be it known that I, JOHANN ORTNER, a subject of the Emperor of Austria-Hungary, residing at Cleveland, in the county of Cuyahoga and State of Ohio, have invented new and useful Improvements in Wheel-Fenders, of which the following is a specification.

This invention relates particularly to wheel-fenders of that class in which the person or object struck is grasped by a spring-acting arm and carried along with the car. Its objects are to provide an improved device of this kind having novel means for tripping and releasing the arms which embrace the person or object struck.

A further object is to improve means for holding the fender in such manner that it may be readily removed and transferred from one end of the car to the other.

20 A further object is to provide an improved fender of the scoop type which is located below the arms referred to and which acts in conjunction therewith to prevent injury to a person hit by the car.

25 In the accompanying drawings, Figure 1 is a side elevation of a car provided with my improvements. Fig. 2 is a top plan view with the arms opened. Fig. 3 is a similar view of the arms closed, and Fig. 4 is a sectional view.

30 The scoop or lower fender will first be described. It consists of curved side arms 6, which are pivotally supported at 7 at the front of the car and have front and rear bars 8 and 9, between which a netting 10 is placed. The 35 rear bar 9 has a rearwardly-extending arm 11, preferably at the middle of the fender, which is pivotally connected to a lever 12, which is fulcrumed at 13 to a bracket 14, depending from the bottom of the car. At the lower end of the 40 lever is an adjustable screw-stop 15, which is arranged to strike at the base of the arm 11 and prevent further drop of the lever.

45 At 16 is a weight hung to the lever and acting to drop the same. Normally the weight on the lever depresses the latter, and owing to the rearward extension of the arm 11 behind the pivots 7 the action is to lift the front end of the fender or lift the same from the ground. When the fender strikes an object,

it turns backward on its pivots until the front 50 bar strikes the ground, thereby effectually preventing any person from slipping under the fender. The regulation of the screw-stop 15 fixes the distance the fender is normally lifted from the ground.

55

The arm or embracing fender will now be described. It consists of a housing 17, to the opposite front corners of which are pivoted by bolts 18 the arms 19. These arms swing horizontally and tend to close by reason of a 60 spring 20, coiled around the pivots thereof. The arms are properly padded to prevent injury to a person struck and have at the outer ends rings 21, through which extend the tripping wire or rope 22. This wire is made of 65 two sections, each of which is fastened to an eye 23 on the front of the car. One section has at the free end a button 24 and is of sufficient length to reach from the frame of the car to the position of the arm on that side 70 when opened, so as to bring the button just inside the arm, as shown in Fig. 2. The other section has a clip 25 of simple construction, consisting of two members which are adapted to grip between them the button and which 75 are held when so gripped by a sliding ring 26. This section of the wire is of a length sufficient to reach from the button through the arm on the other side. The housing 17 consists of a rather heavy metal plate having upper and lower flanges 17^a, and these flanges have holes therein, as at 17^b, to receive the ends 27 of the coiled-spring support or bracket 28, which is fastened to the front end of the car. One of these brackets is provided 80 at each end of the car, and the housing and arms can be lifted off and changed to either end. The housing is properly padded in front, and when it receives the impact of a person or object struck the spring 28 cushions the shock. 85

In operation the trip-wire is threaded through the rings on the ends of the arms, and the latter are forced apart as far as permitted by the stops 22^a thereon. The button 24 is then clamped in the clip 25 with sufficient 90 force to counteract the strength of the spring 20. The wire is thus stretched tight between and in front of the arms, and the latter are

prevented from closing. When a person is struck, he falls against the wire 22 with force sufficient to snap the clip 25 from the button. The holding-wire being thus parted, the restraint on the arms is removed, and they fly together under the pressure of the spring and embrace and hold the person. In combination with this effect the lower fender, first described, acts to pick up the feet of the person and prevent him from falling down from the arms and under the car.

What I claim as new, and desire to secure by Letters Patent, is—

1. A fender pivoted to the frame of the car and having an arm extending behind the pivot, and a weighted lever fulcrumed at its rear end on the car and connected to the arm, and acting to lower the arm and lift the front end of the fender.
2. The combination with the spring-actuated arms, of a retaining-wire formed in two parts connected to the car and extending be-

tween and in front of the arms, and having a connection separable under impact.

3. The combination with a housing, and embracing-arms pivoted thereto, of a yielding bracket supporting the housing, on the car.

4. The combination with a car having a yielding bracket thereon, of a removable housing on the bracket, and spring-actuated arms pivotally supported on the housing.

5. The combination with the spring-actuated arms tending to close, of a connection between the arms, and to the car, retaining the arms open, said connection being breakable under impact, to release the arms.

In testimony whereof I have signed my name to this specification in the presence of two subscribing witnesses.

JOHANN ORTNER.
